[57] **CLAIM**

The ornamental design for a body cooling jacket, as shown and described.

DESCRIPTION

FIG. 1 is a perspective view of a body cooling jacket showing my new design;

FIG. 2 is a perspective view thereof;

FIG. 3 is a rear elevational view thereof;

FIG. 4 is a right side elevational view thereof;

FIG. 5 is a bottom view thereof;

FIG. 6 is a front elevational view thereof;

FIG. 7 is a left side elevational view thereof; and,

FIG. 8 is a top view thereof.

The broken line showing in FIGS. 1 and 2 is for illustrative purposes only and forms no part of the claimed design.
